UNITED STATES PATENT OFFICE.

THOMAS CLARK, OF QUINCY, ILLINOIS.

EXCAVATING-MACHINE.

SPECIFICATION forming part of Letters Patent No. 295,522, dated March 25, 1884.

Application filed June 22, 1883. (No model.)

To all whom it may concern:

Be it known that I, THOMAS CLARK, a citizen of the United States, residing at Quincy, in the county of Adams and State of Illinois, have invented a new and useful Dirt-Excavating Machine, of which the following is a specification.

My invention relates to an improvement in ditching and excavating machines; and it consists in certain improvements in details of construction tending to improve the efficiency of the device and insure its successful operation. In its general plan my machine consists of a frame-work carried upon two pairs of wheels. Gearing on the axle of the forward wheels operates a rotating cylindrical digging and elevating device, which raises the earth to an elevator or endless belt operated independently from the rear wheels. At the lower end of the frame of this belt is a cutter or scraper, and both of these last-named devices are adjustable. The cylindrical digger is carried on a swinging frame pivoted on the forward axle and capable of being locked rigidly into place. The machine, the general principles of which are thus briefly indicated, will be more fully described in connection with the accompanying drawings, in which—

Figure 1 is a side view; Fig. 2, a plan view of the bottom of the excavator; and Fig. 3 is a detail sectional view of the vertical hangers, taken through the said hanger.

A A represent the front and B B the rear supporting-wheels. A' B' are the axles of the respective pairs of wheels, and A² A² the bolsters, all of any suitable construction, the front wheels being pivoted to enable the machine to turn readily. Upon the bolsters is mounted the rectangular frame C, which supports the dirt-carrier, driver's seat, and shipling-levers.

The work of excavation is performed by a rotary excavator, D, journaled in a swinging frame or yoke, E, mounted directly upon the front axle. It is driven by spur-wheels 11, connected to the hubs of the driving-wheels and meshing into pinions 2 2 on the ends of the excavator-journals. On the periphery of the cylinder D are arranged the rows of excavating-tools 3 4. The tools 3 have broad blades,

and those at opposite ends of the rows are inclined in opposite directions, so as to give a draw-cut. The tools 4 are narrow digging-tools, arranged in regular rows alternating with the rows of tools 3.

The swinging frame in which this rotary excavator is journaled is of course adjustable both to vary the depth of cut and to raise the excavator entirely above the ground, for convenience in moving and transporting the machine when not in use. The swinging frame is locked rigidly in position with the excavator at any height above the ground by means of pins 5 5, which pass through holes in its front portion, 6, and through any of a series of holes, 7 7, formed in arms 8 8, projecting from the axle and bolster. The excavator may be stopped by sliding the pinions 2 2 on its journals, they being provided with a groove and feather for that purpose.

The dirt-carrier F is attached to two of the upright posts of the main frame. It consists of inclined sectional side bars, G G, the sections of each hinged together, as shown, suitable cross-braces, and a carrier-belt. (Shown in Figs. 1 and 2.) The lower ends of the side bars are secured, as shown at 9, to the hangers H H, which are rendered adjustable in the frame C, as hereinafter described.

In the lower part of hangers H H is journaled the lower roller of the carrier-belt I. The upper roller is journaled in the main frame. The belt is driven from the rear wheels by spur-wheel 11, on the axle thereof, meshing into an adjustable pinion, 13, on the journals of the roller. With the pinion 13 is formed a flanged disk, 14, on which bears the end of a shipling-lever, 16, which is pivoted in a standard, 15, on the main frame. The lever may be operated from the driver's seat, and has sufficient horizontal movement upon the standard 15 to throw the roller and carrier into and out of gear.

The belt may be provided with any suitable retaining devices for holding the dirt more securely. The dirt, after being carried up on this belt, drops upon a supplementary carrier, which extends at right angles from the side of the frame near the rear thereof. Its upper roller, 17, is driven from the rear axle by a crown-wheel, 18, thereon. This meshes into

a bevel-pinion on the end of a supported counter-shaft, 19. Sprocket-wheels 20 21, respectively keyed to the journal of roller 17 and to shaft 19, are connected by a chain, 22, which 5 thus transmits motion to the endless belt 23.

The hangers H H, which support the lower end of the dirt-carrier, may be formed of one piece of metal, as shown, of arched form and vertically adjustable. At their lower ends is 10 secured a scraper-blade, K, which removes the earth torn up by the rotary diggers. The hangers are adjusted vertically by means of serrated face-plates 24 secured to them. Through slots in these face-plates and in the hangers a 15 bolt, 25, passes, and on this bolt are similarly-serrated plates 26. The bolt is threaded, and nuts 27 may be turned up against the face-plates 26, forcing them into contact with the hangers and holding the latter stationary.

20 In order to prevent the front wheels from turning while the machine is at work, I have provided a sliding locking device, L, which has arms 28 28, which pass through staples 29 30, secured, respectively, to the front of the 25 frame and the bolster. The device, when free, may be suspended from a pin, 31, just below the driver's seat 32.

Having thus fully described my invention, I claim—

1. In an excavator, the combination, with 30 the rotary cylinder having cutters and driven from the forward axle, of a carrier-belt driven independently from the rear axle.
2. In combination with the axle of the forward wheels, a swinging frame mounted on 35 such axle, and a rotary excavator journaled in the frame, and means for adjusting and locking the frame.
3. The swinging frame and the rotary excavator, in combination with the arms and pins. 40
4. The combination, with the hinged section of the dirt-carrier, of the slotted hangers H H, the bolt, and the described locking devices.
5. In a ditching-machine, a pair of swiveled 45 guiding-wheels, in combination with the locking device, substantially as described, for holding the axle and bolster rigidly in line with the main frame.

THOMAS CLARK.
